CLAIM

The ornamental design for an electric bicycle, as shown and described.

DESCRIPTION

FIG. 1 is a top, front, and left side perspective view of an electric bicycle embodying our new design; FIG. 2 is a bottom, rear, and right side perspective view thereof;

FIG. 3 is a right side elevation view thereof;

FIG. 4 is a left side elevation view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is an enlarged and partial perspective view of portion 9 in FIG. 1;

FIG. 10 is an enlarged and partial perspective view of area 10 in FIG. 1;

FIG. 11 is an enlarged and partial perspective view of area 11 in FIG. 1;

FIG. 12 is an enlarged and partial perspective view of area 12 in FIG. 2;

FIG. 13 is an enlarged and partial perspective view of area 1 in FIG. 2;

FIG. 14 is an enlarged and partial perspective view of area 14 in FIG. 2;

FIG. 15 is an enlarged and partial perspective view of area 15 in FIG. 2; and,

FIG. 16 is a top, front, and left side perspective view thereof in a use.

The broken lines in the drawings illustrate portions of the electric bicycle that form no part of the claimed design.

1 Claim, 16 Drawing Sheets
